UNITED STATES PATENT OFFICE.

WILLIAM H. WYMAN, OF OSHKOSH, WISCONSIN.

BUTTON-ATTACHING MACHINE.

1,142,004.

Specification of Letters Patent.

Patented June 8, 1915.

Application filed March 13, 1913. Serial No. 753,966.

To all whom it may concern:

Be it known that I, WILLIAM H. WYMAN, a citizen of the United States, and resident of Oshkosh, in the county of Winnebago, 5 State of Wisconsin, have invented new and useful Improvements in Button-Attaching Machines, of which the following is a description, reference being had to the accompanying drawings, which are a part of this 10 specification.

This invention relates to improvements in button-attaching machines for attaching buttons to shoes or fabrics.

It is one of the objects of the present invention to provide a button attaching machine in which the buttons are placed in a suitable receptacle and automatically fed therefrom to a point of attachment and engaged by the end portion of a coil of wire 20 from which staples are formed to attach the buttons to the material.

A further object of the invention is to provide a button attaching machine in which the attaching wire is fed to the buttons by a 25 lever and other mechanism which is positively actuated by a rock cam.

A further object of the invention is to provide a button attaching machine in which the buttons are fed to the attaching point 30 of the machine by a lever and other mechanism positively actuated by a rock cam.

A further object of the invention is to provide a button attaching machine in which the wire cutter and staple bending mechanism 35 is actuated by a lever and a rock cam.

A further object of the invention is to provide a button attaching machine in which the staple driving mechanism is actuated by a lever and a rock cam.

40 A further object of the invention is to provide a button attaching machine in which the button holder and staple forming mechanism is actuated by a lever and a rock cam.

A further object of the invention is to 45 provide a button attaching machine in which the button hopper is actuated by a lever to properly position the buttons for feeding them to the attaching mechanisms.

50 A further object of the invention is to provide a button attaching machine with a plurality of button hoppers adapted to contain buttons of different styles to permit the easy substitution of the style desired.

A further object of the invention is to

provide a button attaching machine with 55 novel means for engaging and releasing the buttons and feeding them to the point of attachment of the machine.

A further object of the invention is to provide a button attaching machine which 60 may be operated by foot or other power which is of comparatively simple construction, is strong and durable and is well adapted for the purpose described.

With the above and other objects in view, 65 the invention consists of the improved button attaching machine and its parts and combinations as set forth in the claims, and all equivalents thereof.

In the accompanying drawings in which 70 the same reference characters indicate the same parts in all of the views: Figure 1 is a side view of the improved button attaching machine, a portion of the supporting standard being broken away and removed for convenience of illustration and the lower portion of the standard being shown in section; Fig. 2 is a top view of the complete machine; Fig. 3 is a vertical sectional view of the upper portion of the machine taken on 75 line 3—3 of Fig. 8; Fig. 4 is a vertical sectional view thereof taken on line 4—4 of Fig. 3; Fig. 5 is a similar view thereof taken on line 5—5 of Fig. 3; Fig. 6 is another similar view taken on line 6—6 of Fig. 3; Fig. 7 is still another similar view taken on 80 line 7—7 of the same figure; Fig. 8 is a vertical sectional view of the machine taken on line 8—8 of Fig. 3 looking from the opposite side of the machine; Fig. 9 is a transverse 85 sectional view taken on line 9—9 of Fig. 8; Fig. 10 is a vertical sectional view of the button hopper of the machine taken on line 10—10 of Fig. 11; Fig. 11 is a horizontal 90 sectional view of the button hopper taken on line 11—11 of Fig. 10; Fig. 12 is a vertical transverse sectional view taken on line 95 12—12 of Fig. 10; Fig. 13 is a detail view of a fragment of the button feed tube which receives buttons from the hopper; Fig. 14 is a fragmentary detail view, partly in section, of the button attaching portion of the machine; and Fig. 15 is a similar view showing the manner of securing the staple to the material.

100 It may be well at the beginning of the description of the improved button attaching machine to give the general plan of

operation of the machine so that a more clear understanding of the functions of the different mechanisms described may be had, and in following this plan it may be stated 5 that the machine is provided with a button hopper from which the buttons are fed in successive order to a staple forming mechanism, where each button is securely held while the free end of a coil of wire is passed 10 through the eye of the button, the wire then being cut off from the coil to proper length, is formed into a staple. The staple is then driven through the material to which the button is to be attached and clenched. These 15 different operations being performed with each downward and upward movement of the actuating foot lever.

Now referring to the drawings the numeral 20 indicates the base, 21 the standard 20 and 22 the casing or upper frame to which the button attaching mechanism is connected. The upper casing or frame has journaled therein a transversely extending rock shaft 23 which is adapted to be rocked a 25 partial revolution by means of the arms 24 mounted on said shaft. A yoke 25 having its upper ends pivoted to the outer free ends of the arms 24 is medially, adjustably connected to the upper end of a rod 26 extending 30 through the standard 21, and the lower end of this rod is pivoted to a bell crank foot lever 27 which is pivoted to an extension 28 of the base. The forward portion 29 of the bell crank lever projects through the 35 base to a position convenient for the operator. A coiled spring 30 connected at one end to the short arm 31 of the bell crank lever and having its other end connected to the base serves to normally hold the foot lever 40 and the rod and yoke in their uppermost position. The transverse shaft 23 also has mounted thereon between the arms 24 five irregular shaped cams 32, 33, 34, 35 and 36 which are adjustably fixed to the shaft by 45 set screws 37 and rock with said shaft. Another transversely extending shaft 38 mounted in the upper casing or frame of the machine and positioned above and a slight distance toward the rear of the shaft 23 has 50 mounted thereon a series of rock levers 39 which are adapted to transmit motion from the cams to the mechanism mounted on the inclined face 40 of the said casing. The inclined face portion of the upper casing is 55 provided with a flanged cover or top 41 which serves to hold and guard the reciprocating portions of the mechanisms mounted on the said face portion. The rear upper end of this cover has bolted thereto a bracket 60 60 provided with trunnions 43 on which is pivotally mounted the button hopper holder 44. This holder is formed of two arms 45 extending rearwardly from the trunnions and are connected together by transverse 65 portions 46 and 47. The forward trans-

verse portion 46 is provided with an eared member 48 formed to receive the forward end of the guard plate 49 of a button hopper 50 and the rear end portion of the said guard plate is adapted to rest upon the rear transverse portion 47. In order to securely and removably lock the button hopper 50 to the holder 44 the opposite side walls of the hopper are provided with locking recesses 51 into which extend the bolts 52 and 53.

The bolt 52 is fixed to one of the arms 45 and the bolt 53 is spring pressed and is provided with a projecting knob 54 for convenience in withdrawing the bolt from its recess. In order to remove the hopper it is only necessary to move the hopper sidewise a slight distance to clear the fixed bolt, after the spring pressed bolt has been withdrawn from its socket, to reinvoke the hopper rearwardly from the holder.

The button hopper is of rectangular shape with its forward side portions converged to form a discharge funnel 55. In discharging the buttons 50' from the hopper it is necessary that they be so positioned that their eyes or shanks 51' will all extend in the same direction in order to extend the end of the staple wire therethrough. To accomplish this result the bottom portion of the hopper is provided with a plurality of parallel slots 56 which are somewhat narrower than the breadth of the button eyes or shanks to insure the proper positioning of the shanks with relation to the wire feed. The forward ends 57 of the side slots extend at an angle toward and merge with the center slot so that the buttons, the shanks of which are in the grooves, will be discharged from the hopper spout in successive order and in proper position to receive the staple wire. The hopper is agitated to cause the button shanks to enter the slots by means of an adjustable link connection 58 between the hopper holder and the outer end of a lever arm 59 pivoted to a bracket 60 mounted on the frame. The inner end of this arm is connected to a rearward extension 61 of one of the arms 24 by a link 62 so that each time the foot lever is pressed downwardly the button hopper will be swung downwardly to an inclined position and this agitation will cause the buttons within the hopper to fall to the lower end of the hopper and upon the release of the foot lever and the hopper taking its upright position the buttons with shanks which extend into the slots will slide downwardly and forwardly to the discharge funnel 55 of the hopper.

An inner angular guard plate 63 is positioned within and extends transversely of the forward portion of the hopper to prevent the forward movement of buttons which do not have their shanks extending into the slots. The lower wall 64 of this plate is par-

allel to and spaced from the bottom portion 56 of the hopper to just permit the buttons to slide therebetween which have their shanks extending into the slots and thus 5 will prevent the buttons from getting out of the slots during their passage to the discharge end thereof. The guard plate 63 is adjustably supported in the hopper by a bolt 65 which extends through the upper wall of 10 said hopper. A hinged cover 66 is provided for the hopper for convenience in charging the hopper with buttons and the free end of the cover is engaged by a spring latch 67. The guard plate 49 is spaced a sufficient distance 15 below the bottom portion of the hopper to permit the projecting button shanks to pass over said plate.

A button feed tube 68 mounted on the inclined flanged cover or top 41 of the casing 20 has its upper end placed adjacent to the discharge spout of the hopper and is adapted to receive the positioned buttons therefrom. This tube has a slot 69 extending through the entire length of its bottom portion 25 to accommodate the shanks of the buttons and to preserve their positions. The tube is of sufficient size to hold the body of the button and to prevent the button shanks from getting out of the tube slot. The upper portion of the button tube is also provided with a slot 70 to permit the introduction of a tool to slide all of the buttons back 30 into the hopper when it is desired to substitute a hopper containing a different style of button. This upper slot also provides for the use of a clearing tool in case the buttons in any manner become clogged.

The lower open end of the feed tube extends to a point a short distance above the 40 wire feeding and staple forming mechanisms and the buttons are temporarily held at this point by curved flat springs 71 which are positioned on opposite sides of the button feed tube and have their free ends extending into the end recesses 72 of the tube and into the path of movement of the buttons.

A button feed finger 73 pivoted on the projecting stud pin 74' of the upper end of 50 a button feed rock lever 74 is provided with a curved lower button engaging end 75 which is adapted to engage, move and hold each button from the button tube to the point of attachment to the material. The 55 rock lever 74 is pivotally mounted on a stud pin 76 projecting inwardly from the casing 22. The inner end of the rock arm 74 carries a roller 77 which enters the cam groove 32' of the rock cam 32 mounted on the rock shaft 23. The upper portion 77' of this cam groove is concentric with the shaft upon 60 which it is mounted to permit an independent initial movement of the shaft. A cam finger 78 also mounted on the stud pin 74' is connected to the button feed finger 73 by

a pin and recess connection 79 which permits a limited independent movement of the two fingers with relation to each other. This connection is formed by a pin projecting from the hub of the cam finger into a recess 70 in the hub of the button feed finger, the recess being of greater length than the diameter of the pin. A coiled spring 80 surrounding the hub of the finger 73 has its opposite ends connected to a medial portion 75 of the fingers 73 and 78 and serves to yieldingly hold the fingers extending downwardly. The rear free end of the cam finger 78 is provided with a transversely projecting cam pin 81 which is adapted to engage the 80 cam member 82 each time the rock lever 74 is oscillated.

A wire cutting and staple forming reciprocal member 83 mounted in guideways 84 carried by the casing 22 is actuated by 85 the rock lever 85. The reciprocal member 83 is adjustably connected to the rock lever by a turnbuckle link 86' and the rock lever is rocked on its bearing shaft 88 by the roller engagement 86 between the lower end of the 90 rock lever and the cam groove 87 of the cam 33. The upper portion 88 of the cam groove 87 is concentric with the shaft 23 to permit an initial movement of the rock shaft independently of the rock lever 85.

The upper portion of the reciprocal member 83 is provided with a central longitudinal groove 89 in which is slidably positioned a staple clenching punch member 90. This punch is adjustably connected to the rock 100 lever 91 by a turnbuckle 92 and the lower end of the rock lever carries a roller 93 which enters the cam groove 94 of the rock cam 35. The upper portion 95 of this cam groove is also concentric with the rock shaft 105 23, upon which the cam is mounted, to permit an initial movement of the said shaft independently of the rock lever.

The upper forward end portion of the 110 punch member 90 is provided with a centrally located downwardly extending curved groove 96 to accommodate the shanks 51' of the buttons 50' when they are removed from the button tube 68 by the finger 73. The portion of the cover 41 adjacent to the discharge end of the button tube is provided with beveled recessed portion 41' to support the button while being attached to the material and is also provided with a slot 42' to accommodate the shanks of the buttons.

The longitudinal groove 89 of the reciprocal member is of a width approximating the inner width of the attaching staple 97 and the inner walls of the member forming the groove are provided with recesses 98 to receive the legs of the staple and hold said staple in alignment with the clenching die 99 of the anvil 100. The forward end of the reciprocal member is provided with a transversely extending wire 130

recess or groove 101 which serves to engage the staple wire 102 while it is being severed from the wire of the spool 103. The end recess 101 is in alignment with the inner recesses 98 and also serves to guide the unformed staple into the inner recesses while being formed.

The wire from the spool is fed to the staple forming point by means of the cam feed arm 104 pivotally mounted on the upper portion of the casing 22. The rear end of this arm is mounted on the pivot screw 105 and one side edge portion of the arm has a cam 106 projecting laterally therefrom which is engaged by the cam roller 107 journaled on the upper end of the rock lever 108. The lower end of the rock lever is provided with a cam roller 109 which enters the cam groove 110 of the cam 36. The upper end 111 of this cam is also concentric with the shaft and permits the independent initial movement of the shaft 23 as before described with reference to the other cams. A flat spring 112 attached to the casing at one end has its free end bearing against the side edge of the feed arm 104 opposite to the cam, and serves to yieldingly swing the free end of said feed arm toward the button tube. The free end of the feed arm is provided with an upturned angular projection 113 having a wire aperture 114 in one portion through which the wire 102 passes. The inner portion of the projection has a guide groove 115, of a depth half the diameter of the wire, formed therein which is in line with the wire aperture and through which the wire also passes. The portion of the wire engaging the projection is clamped thereto by means of a pivoted spring actuated dog 116 carried by the feed arm which is adapted to grip the portion of the wire between the projection and the free end of the dog during the return movement of the feed arm. As the arm is positively 45 swung outwardly by the engagement of the roller end of the lever arm 108 with the cam portion 106 of the feed arm the outer end of the dog will freely slide on the wire and when the lever arm 108 disengages the cam 50 of the feed arm the spring 112 will yieldingly swing the arm toward the button tube and during this last mentioned movement the dog will grip the wire and feed it forwardly. The free end of the dog is provided with teeth or serrations to get a better grip on the wire.

In order to prevent the return of the wire with the positive movement of the feed arm a pivoted spring actuated dog 117 is provided which co-acts with an upstanding angular projection 118 forming part of one of the guide ways 84. The dog is disposed at an angle with relation to the upstanding projection to provide a gripping action on 60 the wire in one direction of movement of the

wire and to permit the free movement of the wire in the other or the feeding direction. The projection is also provided with a wire aperture 119 and a guide groove 120 similar to the projection 113 of the feed arm. 70

From the projection 118 the wire passes through a wire aperture 121 provided in the gib 122 forming part of the guide 84, and then through the eye of the button shank and the end of the wire butts against the 75 inner face of the opposite gib 123. This gib 122 also serves as one member of the shear and co-acts with the reciprocal member 83 in severing the piece of wire from the coil which is about to be bent in the form 80 of a staple. The distance between the inner faces of the gibs is just the length of the wire forming the staple and the yielding movement of the feed arm 104 in advancing the wire serves to automatically compensate 85 for any variation in feed and to always provide for the end of the wire abutting against the gib 123. The length of swing of the feed arm is controlled by the stop screw 104' which is threaded into one of the 90 guideways 84.

In order to hold the button shank and the medial portion of the severed wire while the wire is being bent to form the staple, a holding and forming lever arm or finger 95 124 is provided which is momentarily swung into button and wire engaging position by the rock cam 34. This forming lever is pivoted on the fixed shaft 38 and extends forwardly, horizontally through a slot 125 in the casing 22 and its free end curves upwardly and is provided with a recessed portion 126 into which the shank of the button extends. The upwardly projecting lug 127 formed by the recessed portion 126 holds the button shank and the wire while the staple 97 is being formed by the reciprocal member 83. 100

The clenching die 99 is provided with two semi-circular recesses 99' which bend the 110 prongs of the staples inwardly toward each other and at a curve toward the material to which the button is attached to securely clench the staple to the material.

The stud pin 74' of the lever 74 has a flat 115 spring 129 connected thereto which bears at its outer end portion on a pin 130 projecting from the button finger 73 to normally hold the said button finger yieldingly in its lowermost position. 120

The casing is provided with side pockets 131 to hold a supply of buttons of different kinds or to momentarily hold buttons which have just been removed from a shoe preparatory to changing their location on 125 the shoe.

A piece of material positioned to have a button attached thereto is indicated by the numeral 132.

In use a supply of buttons are placed 130

within the hopper and the hopper is attached to the hopper holder by sliding its guard plate into engagement with the eared members of the holder and by snapping the bolt into the locking recess of the hopper. Now assuming that the hopper has been oscillated to fill the feed tube with buttons and the foot lever is pressed downwardly the button finger will be swung upwardly and rearwardly by the movement of the button feed rock lever and the engagement of the cam finger with the cam member mounted on the casing. The button finger in moving upwardly will swing to a position over the lower button in the feed tube and as the cam finger slides out of engagement with the cam member the button finger will be yieldingly swung downwardly into engagement with the button by the flat spring carried by the button feed rock lever. Now if the foot lever is released the rock cam will swing the button feed rock lever and the button feed finger forwardly and in swinging forwardly the cam finger will ride up the cam and yieldingly force the button finger downwardly so that in moving forwardly, the button finger will withdraw the lower button from the button tube and slide it downwardly on the inclined slotted portion of the casing cover to material attaching position. At the upper end of the foot lever stroke the roller 107 disengages the wire feed lever 104, and the spring 112 throws the lever 104 inwardly and will yieldingly force the wire through the button shank and against the gib 123. The machine is now in position to attach the buttons to the material interposed between the die and the button, and the foot lever is again depressed. This movement of the foot lever and the cams actuated thereby will slide the reciprocal member forwardly to cut off the wire and bend it into staple formation, and will force the punch member forwardly to drive the staple shanks through the material and into the recessed portions of the die and the die will deflect the shank ends toward each other in a curve to clenching engagement with the material. When the foot lever is again released the feed finger will again swing forwardly with a button and the wire will be extended through the button eye as before described so that another button is in position to be attached. The movement of the foot lever will also oscillate the button hopper to shake the buttons into the button slots and into the button tube.

When it is desired to use different kinds of buttons it is only necessary to slide the buttons within the button tube back into the hopper and disengage the hopper from the hopper holder and substitute another hopper having the kind of buttons desired and then proceed as before described.

From the foregoing description it will be

seen that the button attaching machine is of simple construction and is well adapted for the purpose described.

What I claim as my invention is:

1. A button-attaching machine comprising a casing, a button hopper pivotally connected to said casing, a wire-feeding mechanism carried by the casing, a wire-cutting and staple-forming and setting mechanism carried by the casing, means for feeding buttons from the button hopper to the staple-forming and setting mechanism, a series of levers pivoted to the casing and connected to the mechanisms, a rock shaft journaled in the casing, means connected to said rock shaft and button hopper for rocking said button hopper, a series of rock cams carried by the shaft for actuating the levers and means for operating said rock shaft.

2. A button-attaching mechanism comprising a casing, a button hopper pivotally secured to said casing, a wire-feeding mechanism carried by the casing, a reciprocal mechanism for cutting the wire and forming and setting a staple therefrom mounted on the casing, mechanism for moving buttons from the button hopper to the reciprocal mechanism, a rock shaft, means connected to the rock shaft and the hopper for oscillating the hopper, a series of cams mounted on said shaft, levers actuated by the cams and having connections with the different mechanisms, and means for operating said rock shaft.

3. In a button-attaching machine, the combination of a casing, staple forming mechanism comprising a reciprocal forming member and an oscillating forming finger co-operating with said member to form the loop and legs of the staple, staple-setting mechanism comprising a reciprocal punch member and a clenching die, levers pivotally mounted in the casing and connected to said reciprocal forming member and said reciprocal punch member respectively, a rock shaft journaled in the casing, a series of rock cams carried by said shaft for actuating said levers and said forming finger, and means for operating said rock shaft.

4. In a button-attaching machine, the combination of a casing, a bearing shaft mounted in said casing, staple forming mechanism comprising a reciprocal forming member mounted on the casing and an oscillatory forming finger pivotally mounted on said bearing shaft, staple-setting mechanism comprising a reciprocal punch member slidably mounted on said reciprocal forming member and a clenching die, levers pivotally mounted on said bearing shaft and connected to said reciprocal forming member and said reciprocal punch member respectively, a rock shaft journaled in the casing, a series of rock cams carried by said rock shaft for actuating said levers and said

forming finger, and means for operating said rock shaft.

5. In a button-attaching machine the combination with a casing, staple-forming mechanism comprising a reciprocal forming member having a guideway therein and a forming finger coöoperating with said member to form the loop and legs of the staple, and staple-setting mechanism comprising a reciprocal punch member slidably mounted in said guideway and a clenching die, of means for operating said mechanisms comprising levers pivotally mounted in the cas-

ing and connected to said reciprocal forming member and said reciprocal punch member respectively, a rock shaft journaled in the casing, a series of rock cams carried by said rock shaft, and means for operating said rock shaft.

In testimony whereof, I affix my signature, in presence of two witnesses.

WILLIAM H. WYMAN.
